Charles Geuner, of Cincinnati, Ohio
Assignor to
M. Greenwood & Co. of the same place.
Letters Patent, No. 622, Dated January 24th, 1854.

The schedule referred to in these Letters Patent, and making part of the same.

To all whom it may concern:

Be it known that Charles Geuner, of the City of Cincinnati, County of Hamilton and State of Ohio, have invented or produced a new and original design for a stand for Shovels and Tongs, and do hereby declare that the scroll and leaf work, represented in the annexed drawings, marked Nos. I. II. is a full and exact description of the same.

What I claim, and desire to secure by Letters Patent is the new design for a pair of shovel and tong stands, consisting in the ornamental figures set forth in the accompanying drawings.
